UNITED STATES PATENT OFFICE.

JOHN REICHERT, OF RACINE, WISCONSIN.

TRACTION OR ANTISKID DEVICE.

Application filed November 18, 1919. Serial No. 338,829.

To all whom it may concern:

Be it known that I, JOHN REICHERT, a citizen of the United States of America, and resident of Racine, Racine County, State of Wisconsin, have invented certain new and useful Improvements in and Relating to Traction or Antiskid Devices, of which the following is a specification.

This invention relates to certain improvements in traction or anti-skid devices; and the objects and nature of the invention will be readily understood by those skilled in the art in the light of the following explanations of the accompanying drawings illustrating what I now believe to be the preferred mechanical expression or embodiment of my invention from among other forms, constructions and arrangements within the spirit and scope thereof.

The invention relates to anti-skid devices of the clamping bar type wherein clamping bars to which the traction chains are coupled are arranged at the inner and outer sides of the wheel, traversing usually two spokes and clamped thereto by cross bolts located between the spokes, and the particular object of this invention is to render these clamping bars extensible to adapt the same to wheels of different diameters, and to wheels having differently spaced spokes or differently sized spokes.

With this and other objects in view, the invention consists in certain novel features in construction and in combinations and arrangements as more fully and particularly set forth and specified hereinafter.

Referring to the accompanying drawings:—

Fig. 1, shows a portion of a wheel in side elevation equipped with anti-skid devices in accordance with my invention.

Fig. 2, is a section on the line 2—2, Fig. 1.

Fig. 3, is a section on the line 3—3, Fig. 1.

Fig. 4, is a detail perspective of the two clamping bar units or members with their sections in various positions, one section being partially broken away, also one of the clamping bolts being shown.

In the drawings, I show a pair of clamping bar units or members adapted for application to the inner and outer sides of a wheel to traverse the opposite side faces of at least two spokes *c* and to project beyond said spokes. These two bars are clamped to the spokes by an intermediate cross bolt 4,

extending through the central portions of the bars and located in the space between the two spokes, and by two similar end bolts 4 passing through the projecting ends of the bars and located beyond the opposite edges 60 of said spokes from the central bolt 4.

These bars are elongated and approximately straight to form a chord of the inner circle of the wheel felly (or rim) *b* with their ends firmly abutting and seated on the inner surface of the felly. To this end, the inner edges of the ends of the bars are longitudinally curved, inclined or bevelled to form shoes 3 to give the bar ends firm seating or bearing on the felly surface.

The bar to fit the spokes and felly at the inner side of the wheel is indicated generally or as a unit by the reference numeral 1, and the complementary bar for the outer side of the wheel by 2.

The traction chains or other suitable traction devices 6 pass over the wheel tire *a* and each chain is in this instance, provided at both ends with flat end chain loops 6^a. The ends of the bar units are provided with attaching devices adjacent to the end bolts 4 and over or adjacent to the shoes 3, to receive or enter said chain loops 6^a and thereby attach the ends of the chains to the ends of the respective bars so that the pull of the 85 chains on the bars will be transmitted to the felly through seats 3. In other words, the ends of the bars receiving the chain pull are directly sustained and backed by the felly and braced and held by the end bolts.

In the particular example illustrated, a pair of clamping bars or units is constructed to secure a pair of traction or anti-skid elements, such as chains, to the wheel, although I do not wish to so limit all features of my 95 invention. In this example, one clamping bar or unit is provided with chain retaining fingers 7, here shown as hooks, but I do not wish to so limit my invention, and the other bar or unit with chain retaining lugs or fingers 8, having transverse perforations to removably receive chain retaining or stop means, such as cotter pins 9.

The ends of the units are formed with these fingers 7 and studs 8 so that, in this 105 example, each finger or stud is backed and supported by a shoe 3.

The studs extend laterally in this instance, from side faces of the clamping unit 2, and the fingers 7 project inwardly (i. e. toward 110

the wheel axis) from the inner edges of the offset or reduced ends (shoes 3) of the clamping unit 1.

After the clamping bar units have been 5 properly positioned on and clamped to the wheel, the required number of traction chains are applied and coupled to the wheel through the medium of said clamping bars. Each chain is first attached to the inner bar 10 1 of its set by applying one end link 6^a to a hook 7. This loop is applied by holding the same in a position perpendicular or radial to the inner surface of the felly and then moving the link toward the hook so that the 15 free end of the link will pass between the felly surface and extremity of the hook bill 7'. The link can thus be placed on the hook and when the chain is passed around the tire a the inner end of the link 6^a will rest 20 in the hook socket 7^a (see Fig. 3) and the side bars of the link will rest in the sockets 7^b in the inner edge of the bar at both sides of the hook. The opposite end link 6^a of the chain is then dropped over the corresponding 25 lug 8 of the outer bar 2, and locked thereon by the removable cotter pin 9 or other suitable locking device.

The spacing and sizes of the spokes vary in different makes or types of vehicles wheels 30 of like diameter, and wheels of different diameters have different spoke sizes and arrangements. It has been difficult heretofore to adapt anti-skid devices of this general clamping bar type to different wheels where 35 the sizes and spacing of spokes vary. In fact, it has been necessary to provide different size clamping bars for the different wheel sizes. To the best of my knowledge and information it has not been possible to apply 40 this general type of anti-skid heretofore known to wheels varying substantially in spoke spacing and arrangement.

In order to render the clamping bars of 45 my invention applicable to approximately all sizes of wheels having various spoke spacing and arrangement and to wheels of the same diameters but having different spoke sizes and spacing, I so form each bar as to render the same extensible or longitudinally adjustable so that the bars of a 50 pair can be adjusted to traverse and project beyond at least two spokes with their end shoes properly seating on the wheel felly and so that the various cross bolts can be 55 located as required between the spokes.

In the particular example illustrated, each clamping bar is composed of two complementary longitudinal sections, each section is in one piece and is composed of an end 60 portion 10 of the bar unit and a straight longitudinal shank forming a portion of the intermediate length of the bar unit. The shank 11 of one section is straight and flat and of reduced thickness and vertical width, 65 while the shank 12 of the complementary sec-

tion is of full width and full thickness except for a longitudinal central slideway or socket 13 that snugly receives the flat shank 11 of the other section and provides longitudinal top and bottom edges or flanges 14 fitting the edges of the flat shank 11 and maintaining the two shanks in parallelism.

It will be observed that the central or intermediate portion of the bar is formed by two shanks and that these shanks telescope 75 or slide one on the other as the bar is increased or decreased in length.

The bar ends, formed by the heads 10 of the shanks have longitudinally elongated transverse bolt holes 15, to receive the end 80 clamping bolts 4.

The shank of each bar section has a longitudinal series of transverse bolt holes 16 and these bolt holes are located so close together as to open into each other and thus form an elongated longitudinal slot in the shank throughout the greater portion of the length thereof with the top and bottom edge walls of the slot correspondingly notched. The slot 16 of one shank is aligned with the slot of the other shank, and these slots are 85 to receive the central or intermediate clamping bolt 4 (or bolts if more than one bolt is used to tie together the intermediate portions of a pair of bars). The central bolt 4 will then lock the two sections together 90 against longitudinal movement because of the notched edge formation of the slots 16.

In applying the clamping bars the sections of each bar of the pair of bars are 100 moved longitudinally one on the other, until the bar shoes 3 rest on the wheel felly at the elevation that brings the bolt holes 16 and slots 15, in such positions with respect to the wheel spokes that the end bolts can be located between spokes and outside of the two spokes between the pair of bars and so that the center bolt can be located at the desired point about midway between the two spokes. The elongated end bolt holes allow a certain 110 amount of adjustment to the end bolts to bring them to the desired positions with respect to the two spokes. The closely arranged series of overlapping bolt holes that form the slots 16 permit close adjustment of 115 the central bolt and also lock the two sections of each bar together when the bolts are applied.

The bolts 4 are preferably applied from the inner sides of the wheels so that the bolt heads will fit the inner clamping bar, permitting application of the clamping nuts 4^a to the projecting bolt ends at the outer side of the wheel. If so desired, spring locking washers 4^b can be interposed between the outer clamping bar 2 and nuts 4^a, but my invention is not concerned with such washers. In the particular example illustrated by Fig. 4, the overlapping bolt holes 16 in the shank 11 of the inner clamping unit, are angular in 130

formation to receive the angular end portion of the intermediate bolt 4 to lock said bolt against rotation.

I do not wish to limit my invention to 5 anti-skid devices for truck wheels, as it can be adapted for use on other vehicle wheels.

With the exception of the sectional and longitudinally adjustable features of the clamping bars involved, I do not herein 10 make claim broadly to the anti-skid devices shown, as such anti-skid devices with the exception of the sectional bar formation are shown and claimed in my pending application filed Nov. 17, 1919, S. No. 338,490 for 15 anti-skid devices for vehicle wheels.

It is evident that various changes, modifications and variations might be resorted to without departing from the spirit and scope of my invention as defined by the following claims and hence I do not wish to limit myself to the exact disclosure hereof.

What I claim is:—

1. Means for securing traction chains to a wheel comprising longitudinally extensible clamping bars, means for coupling the chain ends to the bars, and clamping means for the bars, each bar embodying overlapping sections, said clamping means extending transversely through said bars in a direction to clamp the sections together and the bars to lateral side faces of a wheel.

2. Means for securing an anti-skid chain to a wheel, comprising an elongated clamping unit embodying longitudinally overlapping sections whereby said unit is rendered adjustable as to length, and means for clamping said unit to a lateral surface of a wheel, said means extending transversely of said sections of the unit to clamp said sections together when clamping the unit as an entirety to the wheel, said unit formed with chain attaching means.

3. Means for securing a traction chain to a wheel embodying a pair of elongated clamping bars, and means for clamping said bars against opposite side faces of several spokes of a wheel, each bar having end chain attaching means, each bar composed of two sections abutting at their side faces and adjustable longitudinally one on the other to render the bar extensible, said clamping means arranged transversely of said sections and clamping the same together.

4. Means for securing a traction chain to a wheel embodying a pair of clamping bars having chain attaching means, said bars having transverse bolt holes at both ends and the central portion, and transverse clamping bolts passing through said holes and adapted to be arranged between spokes of the wheel, each bar being longitudinally extensible and locked in longitudinal adjustment by the central clamping bolt.

5. Means for securing traction chains to a wheel embodying a pair of clamping

bars, at least one of said bars composed of two longitudinal sections, each section composed of a shank and a bar end, the shanks of the two sections longitudinally overlapping and slideable longitudinally one on the other and formed with longitudinal series of alined bolt holes, said bars having chain attaching means, and a transverse bolt adapted to said bolt holes.

6. Means for securing traction chains to a wheel embodying clamping bars, each bar at its ends formed to fit the wheel felly, and having transverse bolt holes and traction chain attaching means, at least one bar composed of two longitudinal sections having overlapping shanks slideable longitudinally to render the bar extensible, and clamping bolts for said bar ends and for said shanks whereby said shanks are clamped together and said bars are secured to side faces of a wheel.

7. Means for securing traction chains to a wheel embodying a longitudinal elongated clamping bar having traction chain attaching means, said bar composed of two sections, each section embodying a bar end and a longitudinal shank, said shanks longitudinally overlapping and slideable on each other, one shank having a longitudinally depressed slideway receiving the other shank, said shanks having alined longitudinally elongated notched-edge transverse bolt slots, and a clamping bolt adapted thereto for clamping said shanks together and said bar against the side face of a wheel.

8. Means for securing a pair of anti-skid chains to a vehicle wheel, comprising a pair of bars formed at their side faces to fit opposite lateral faces of several spokes of a wheel and at their outer edges to abut the wheel felly, said bars having transverse bolt holes, and a transverse clamping bolt adapted thereto to pass between spokes and clamp the bars against the spokes, one of said bars having its ends formed with chain coupling means, said bar formed in longitudinally overlapping sections fitting together at their side faces and adapted to be traversed by said bolt for locking the sections together.

9. Means for securing an anti-skid chain to a vehicle wheel, comprising an elongated chain attaching bar formed with a side face to fit a lateral side surface of a wheel, said bar composed of longitudinal sections abutting at their side faces and adjustable one on the other to vary the effective length of the bar, and a transverse clamping bolt for clamping said sections together and the bar against the side face of a wheel, said sections being so relatively formed as to prevent relative longitudinal slipping of the sections when the bolt is loose.

10. Means for securing an anti-skid chain to a vehicle wheel, comprising an elongated

chain attaching bar formed with a side face to fit a lateral side surface of a wheel, said bar composed of longitudinal sections abutting at their side faces and adjustable

5 one on the other to vary the effective length of the bar, and a transverse clamping bolt for clamping said sections together and the bar against the side face of a wheel.

11. Means for securing an anti-skid chain
10 to a vehicle wheel, comprising a bar having chain attaching means, said bar formed to fit against a lateral side face of a wheel, said bar embodying longitudinally adjustable sections whereby the effective length of the
15 bar can be varied, said sections fitting side to side and having alined series of bolt holes, the holes of each series closely arranged to merge into each other, and a transverse bar-clamping bolt adapted to said holes to clamp

the sections together, whereby the bolt must 20 be removed from the sections to permit longitudinal adjustment thereof to vary the length of the bar.

12. Means for securing an anti-skid chain to a vehicle wheel, comprising a bar having 25 chain attaching means, said bar formed to fit against a lateral side face of a wheel, said bar embodying longitudinally adjustable sections whereby the effective length of the bar can be varied, said sections fitting 30 side to side and having alined series of bolt holes, and a transverse bar-clamping bolt adapted to said holes to clamp the sections together, whereby the bolt must be removed from the sections to permit longitudinal ad- 35 justment thereof to vary the length of the bar.

JOHN REICHERT.
